UNITED STATES PATENT OFFICE.

WAINWRIGHT B. GERVAIS AND JOHN C. WILMOT, OF CHICAGO, ILLINOIS, ASSIGNEES
TO VARIETY FIRE DOOR COMPANY, OF CHICAGO, ILLINOIS, A CORPORATION OF
ILLINOIS.

INTERLOCK FOR ELEVATOR DOORS AND THE LIKE.

Application filed June 7, 1924. Serial No. 718,448.

To all whom it may concern:

Be it known that we, WAINWRIGHT B. GERVAIS and JOHN C. WILMOT, citizens of the United States, residing at Chicago, in the county of Cook and State of Illinois, have invented a certain new and useful Improvement in Interlocks for Elevator Doors and the like, of which the following is a full, clear, concise, and exact description, reference being had to the accompanying drawings, forming a part of this specification.

This invention relates to interlocks for elevator doors and the like, more particularly to interlocks for preventing starting of the elevator car from a floor with the door or doors leading thereto open, and its objects are the provision of a generally improved device in which the uncertainty of operation of the means for rendering the elevator drive means ineffective is avoided and in which positive actuation of said means is secured with the releasing movement of the latch, also a device that is simple and may be economically produced.

While our invention is particularly adapted for use in connection with that class of elevators which are operated by an electric motor and with that class of doors or closures which include vertically movable sections, it is to be understood that the invention is not limited to use with a particular type of elevator, elevator operating means or closure, but may be employed wherever found adaptable.

The invention is illustrated in the accompanying drawings, in which—

Fig. 1 is a fragmentary elevation of a door showing an embodiment of the invention in connection therewith;

Fig. 2 is an enlarged elevation along the door guide showing the cover of the circuit interrupter removed and the interlocking connection between the interrupter and the door latch;

Fig. 3 is a fragmentary horizontal section through the door guide and adjacent jamb;

Fig. 4 is a fragmentary elevation of a door showing the invention in connection with a latch of the type which latches the door at the center or intermediate the vertical guides; and

Fig. 5 is a fragmentary detail view partially in section of the interlock plunger and

swinging arm showing one form of mechanical connection therebetween. 55

In the embodiment shown in Figs. 1, 2 and 3, the elevator 5 operates vertically in the shaft 6, and 7 designates the wall between said shaft and the respective floors, for example, said wall 7 having an opening or doorway 8 along the jambs or sides of which are secured the vertical guides 9. The door shown comprises an upper section 10 and a lower section 11, the lower and upper edges 12 and 13, respectively, of which meet across the doorway when the door is closed, and said sections 10 and 11 move vertically 60 away from each other in opening, as well understood in the art. 65

The latch mechanism comprises a latch plate or disc 20 pivoted centrally at 21 to the lower door section 11 just below the frame along the upper edge thereof. Secured to the disc 20 and projecting radially therefrom is a handle 22 by means of which the disc 20 may be turned or rotated about its pivot 21. Pivoted to the disc or plate 20 at 23 and 24, respectively, are two arms or latch bars 25 and 26. The latch bars 25 and 26 extend horizontally toward opposite sides of the door and their free ends are adapted to project through the frames along the opposite sides of the door to overlie stops 28 secured to the vertical guide members 9. A spring 30 normally maintains the handle 22 in substantially the position shown, and the latch bars 25 and 26 in their projected position from the opposite sides of the lower door section 11. 70 75 80 85

When the panels 10 and 11 are brought together the arms or latch bars 25 and 26 are sprung into place over the stops 28, thereby locking the door closed. Opening of the door necessitates withdrawal of the latch bars 25 and 26, and this is accomplished by rotating the disc 20 by means of the handle 22 in a clockwise direction (Fig. 1), the pivoting 23 and 24 of the latch bars to the plate 20 being off center or eccentrically disposed with respect to the pivot 21. The latch as thus described is a typical side locking latch and we lay no claim here broadly to such a latch. Its details may be varied to suit the requirements of different installations. 90 95 100 105

The elevator car 5 is driven or operated, in the present instance, by an electric motor

shown diagrammatically at 35 in Fig. 2. The particular disposition of this motor and the driving connections between it and the elevator car form no part of the present invention and they have, therefore, been omitted. The motor circuit includes conductors 36 which lead up into a box or housing 37 mounted, for example, on the guide 9 adjacent the outer end of the latch bar 26. The conductors 36 may be enclosed in a conduit 38 extending up and secured to the bottom of box 37. Within the box 37 the ends of the conductors, from which the insulation is removed, have electrical connection with contacts 40 and 41 mounted upon an insulating block 42.

A bridging contact 43 pivoted at 44' to a projection on the lower end of an arm 44 is adapted for bridging contact with contacts 40 and 41 to close the motor circuit and for movement out of engagement with said contacts to open the motor circuit. The arm or lever 44 is pivoted within the box 37 at 45. Mounted for reciprocation in the outstanding flange of the guide 9 and in the adjacent wall of the box 37 is a plunger 48. A pin or screw 49 threaded at 50 into the inner end of plunger 48 projects through an elongated slot 51 in the upper end of arm 44 and is provided at its outer end with a head or cotter pin 52 whereby the plunger 48 and arm 44 are mechanically connected, so that upon movement of the plunger in either direction the arm 44 will be swung about its pivot 45 thereby.

The coiled spring 55 interposed between a lateral wall or web on arm 44 and the adjacent wall of box 37, normally tends to turn the arm 44 in a counterclockwise direction about its pivot 45. A weight or arm 56 pivoted at 57 is weighted above and off center to the left (Fig. 2) with respect to its pivot 57, and this arm has a nose 58 which engages the adjacent edge of arm 44 and by gravitation acts cumulatively with spring 55 to swing arm 44 about its pivot 45. The box 37 may be provided with a suitable cover 60.

The outer end of reciprocable plunger 48 has a flange or head 62 which engages in a notch 63 in the upper edge of the adjacent end of latch bar 26. Notch 63 terminates in a shoulder 64 at one end which cooperates with the head 62 in the latching movement of the latch bar, and a lug 65 at the opposite end of the notch engages or cooperates with the head 62 in the releasing movement of the latch bar. An interlocking engagement is thereby effected between the plunger 48 and the adjacent end of the latch bar 26, so that the plunger is actuated by the latch bar in its movement in each direction.

From the foregoing, it will now be apparent that when the upper and lower panels

of the door are brought together the latch bars spring into place over the stops 28 and, at the same time, the engagement of shoulder 64 with head 62 positively forces the plunger 48 outwardly and thereby the 70 arm 44 in a clockwise direction about its pivot against the action of spring 55 and weighted arm 56, and closing the motor circuit by engagement by bridging contact 43 with contacts 40 and 41. The door having been completely closed and latched, the motor circuit is completed so that the elevator car may be started up and moved from the floor with which the opening 8 communicates. In opening the door, and in the inward releasing movement of the latch bar 26, the lug 65 engages the head 62 and thereby positively moves the plunger 48 outwardly and swings the arm 44 in a counterclockwise direction through the mechanical connections 49 and 52, opening the motor circuit at 43—40, 41, so that the elevator car cannot again be started until the latch is set.

The difficulties encountered, where an arm such as the arm 44 is merely released by the releasing movement of the latch and a spring is relied on to open the motor circuit are avoided. If the spring sticks or the parts become tight because of infrequent use, the latch bar will either positively open the motor circuit in spite of any sticking or tightness, or it will be impossible to unlatch the door. If the door cannot be unlatched or opened, a closed motor circuit is immaterial.

While we prefer an interlocking connection between the plunger 48 and the latch bar, and also a mechanical connection between the arm 44 and the plunger, it will be apparent that the advantages of the invention may be partially secured by employing the interlocking connection between the plunger and latch bar without a mechanical connection between the plunger and arm 44. In such case, the releasing movement of the latch bar would positively assure movement of the plunger which is the part which is subjected to the weather, and the spring and weighted arm, all of which are enclosed within the box 37, could be relied on for swinging the arm 44 to open the motor circuit. The gravitation of the arm 56 against the arm 44, in a direction to open the motor circuit would tend to assure positive swinging of the arm 44 in the direction of its opening movement in spite of sticking of said arm or failure of spring 55.

In Fig. 4 we have shown the invention in connection with a latch of the typical center latch type, in this case, the latch arm 70 is pivoted at 72 to a bracket 73 mounted upon the upper door panel 74 centrally between the opposite sides thereof and adjacent the

lower edge of said panel. The latch bar 70 has a handle 75 and its depending arm extends down through the frame 76 along the bottom of upper panel 74 and through the frame 77 along the top of lower panel 78. The lower end of this depending arm has a catch 80 which engages under the frame 77 of lower panel 78 and thereby locks the upper and lower panels together in closed position. The openings 81 are elongated to permit swinging of the depending arm of the latch bar and to permit separation of the upper and door panels when said bar is in the position shown in dotted lines. 15. The circuit interrupter 82 is mounted as before upon the guide 9' adjacent the meeting edges of the upper and lower door section, and its reciprocable plunger 83 has a head 84 which engages in a notch 85 in the outer end of an interrupter operating bar 86 which is pivoted at its opposite end at 87 to the latch bar 70. As before, an interlocking engagement between the plunger 83 and bar 86 is thereby secured, so that the 20 plunger is positively actuated in the releasing as well as in the setting or latching movement of the latch bar 70. The slots 85 and 63 are in each case preferably of sufficient length to provide a slight play or 25 clearance between their opposite ends and the head of the plunger, permitting initial movement of the bar without actuating the plunger and complete unlatching and latching movement of the bar without moving the 30 plunger the entire latching and unlatching distance.

We do not intend to be limited to the precise details shown and described.

We claim:

40 1. In combination, a movable carrier, a drive motor therefor, a closure, a latch for said closure, a circuit interrupting device for the motor, said device having a reciprocable plunger interlocked with said latch, a pivoted circuit closing and opening arm mechanically connected with said plunger for actuation therewith, and a weighted arm pivoted adjacent said first arm and acting upon it in the direction of its movement to circuit opening position.

45 2. A circuit interrupter having a reciprocating plunger, a pair of contacts, a centrally pivoted arm having one of its ends mechanically connected to said plunger and

55 a bridging contact fastened thereto at the opposite end, and a weighted arm pivoted adjacent said first arm and acting upon it in conjunction with said plunger for swinging said bridging contact into and out of contact with said pair of contacts.

60 3. In combination, a casing, an arm pivoted to a wall of said casing, a pair of contacts within said casing, a bridging contact for said pair of contacts connected to one end of said arm, and resilient means disposed between one wall of said casing and said arm for normally urging said bridging contact away from said pair of contacts.

65 4. In combination, a casing, an arm pivoted to one wall of said casing, a pair of contacts within said casing, a bridging contact for said pair of contacts connected to one end of said arm, resilient means disposed between one wall of said casing and said arm for normally urging said bridging contact away from said pair of contacts, and means adapted to bear against the opposite end of said arm for aiding said resilient means in normally urging said bridging contact away from said pair of contacts.

70 5. In combination, a casing, an arm pivoted within said casing, a pair of contacts within said casing, a bridging contact for said pair of contacts connected to one end of said arm, means adjacent each end of said arm for normally urging said bridging contact away from said pair of contacts, and manually operative means mechanically connected to one end of said arm for positively moving said bridging contact into or out 75 of engagement with said pair of contacts.

80 6. In combination, a movable carrier, a drive motor therefor, a closure, a latch for said closure, a circuit breaking device for said motor, said device having a reciprocable plunger interlocked with said latch, a pivotally mounted arm mechanically connected to said plunger at one end, a pair of contacts, and a bridging contact for said pair of contacts connected to said arm, the movement 85 of said arm about its pivotal mounting serving to positively move said bridging contact into or out of engagement with said pair of contacts.

100 105 In witness whereof, we hereunto subscribe our names this 4th day of June, 1924.

WAINWRIGHT B. GERVAIS.
JOHN C. WILMOT.
